DRY GLAZING PROCESS

Filed Jan. 12, 1931

Inventor

George F. Wilde

By *Clarence O'Brien*
Attorney

UNITED STATES PATENT OFFICE

GEORGE F. WILDE, OF KEYPORT, NEW JERSEY

DRY GLAZING PROCESS

Application filed January 12, 1931. Serial No. 508,253.

My present invention relates to a process of applying glazes to ceramic articles, such as pottery, tiles and the like, and making the articles ready for firing.

5 The said process may be carried out by means of the apparatus disclosed and claimed in Letters Patent 1,792,788 of February 17, 1931 to myself and Bennet K. Eskesen. It may, however, be carried out by other forms 10 of apparatus.

The object of the invention constituting the subject of this application is to improve upon the products obtainable by presently known methods of applying glazes to ceramic 15 articles preparatory to firing, by providing a simplified, novel process which involves fewer and less troublesome and expensive operations, and which I term a process of dry glazing of ceramic articles, and which results not only in a marked saving in time and 20 material and amount of machinery required but also in a product of superior quality and uniformity.

This and other objects of the invention, its 25 nature, and its composition and arrangement and combination of parts and the steps and operations and their sequence involved will be readily understood by any one acquainted with the art to which this invention relates 30 upon considering the following description and explanations and the appended drawing.

The drawing shows a side elevational view 35 partly in section of a glaze applying machine which may be used to carry out the process of the invention.

It should be noted that I do not intend to specifically claim as a part of my invention the machine described herein as it constitutes 40 only one type of machine adapted to be employed in carrying out my process and it is my intention to claim the process only, whether carried out manually or by a suitable machine. The machine described and alluded to herein is brought into this application 45 only for the sake of clarity in explaining the steps and operations of my process and their sequence.

The process constituting my invention consists broadly in coating the face of a ceramic 50 article with an adhesive such as glue, water,

oil or the like, distributing evenly a quantity of pulverized glaze material on a resistant surface to the desired depth, and pressing the face of the article upon the surface to cause the glaze to adhere to the face of the article. 55 The same result may be achieved in an inferior manner by applying to the face of a ceramic article a coating of adhesive and then sieving or otherwise depositing a coating of glaze material thereon. 60

The resistant surface may be either elastic or resilient within practical limits or it may be rigid according to the type of glazing to be done. The adhesive may be such as to dry 65 into the face of the article and to reappear upon application of the glazing material thereto, or it may be of any suitable character not specifically alluded to herein, since in claiming the process herein, I do not limit myself to the use of the material alluded to 70 herein, but I include all and any materials which may be found to be suitable for carrying out the process.

In the attached drawing of a tile glazing machine, the numeral 5 designates a suitable 75 frame on which is mounted a conveyor belt 6 on longitudinally spaced opposed rollers 7, and the numeral 8 refers to a belt tightener idler. Over the horizontal flight of the conveyor belt 6 at one end of the frame is placed 80 a hopper 9 having a synchronized measuring discharge mechanism for evenly dispensing glaze material upon the belt to a predetermined depth. Over the said horizontal flight of the belt inward of the said hopper is an 85 adhesive applying belt and presser roller mechanism 10. It comprises an adhesive reservoir 11 in which the horizontal endless adhesive applicator belt 12 runs, a series of tile guides 13 and a pair of pressure rollers 18 and 19 placed in succession as shown. Over the end of the conveyor belt 6 opposite the hopper 9 is a finishing pressure roller mechanism 16. A brush 17 contacts the conveyor belt for removing undesired material therefrom. 95

I shall now state how the above described machine may be employed to carry out the process of my invention in glazing small tiles, such as mosaic tiles, which are ordinarily 100

very difficult to properly glaze. Of course, it will be understood that in the case of certain forms of tiles, or in the case of other round or curved or irregularly shaped ceramic articles, the machine used must be provided with means to turn or roll the ceramic articles in contact with the glaze applying means.

In using the described machine, the tiles are first attached to a sheet of paper or the like in spaced relation to each other. The sheet of tile is then faced downwardly and placed on the tile guides 13 which are arranged to come between the rows of tiles on the sheet. Assuming that there is a quantity of adhesive already taken up by the adhesive applicator belt 12 from the reservoir 11, the starting of the machine will cause the belt 12 to deposit a coating of the adhesive upon the face of the tile, and the sheet of tile will then be moved to the pressure roller 18 which will press the deposited adhesive thoroughly on or into the faces of the tile. A transfer roller 19 forcibly contacts the adhesive covered tile faces with the conveyor belt 6 which has been previously covered to the desired depth with glaze material in a manner already described. This contact causes the tile to pick up a quantity of glaze material. The next step is the passing, by the movement of the conveyor belt 6, of the tile under the finishing pressure roller mechanism 16. This mechanism consists of a pair of vertically aligned rollers, the lower of the rollers being under the belt 6 and positioned to slightly elevate the portion of the belt 6 where the belt passes thereover. The upper roller is positioned to engage the back of the sheet of tile as it passes thereunder. Of course, it is obvious the rollers cooperate simultaneously to thoroughly embed the glaze material in the adhesive coated face of the tile and by compressing the tile, condition and finish the tile for firing. The finished tile comes off the conveyor belt 6 beyond the roller mechanism 16.

It is to be definitely understood that I do not desire to limit the application of this invention to the particular modifications set out herein to illustrate the principles and operation of the invention, and any changes may be made in materials and in structure and arrangement and cooperation of parts and in the sequence and duration of steps or operations consistent with the spirit and scope of the invention as claimed.

Having thus described the invention, what is claimed is:—

1. A process for glazing ceramic articles comprising applying a coating of adhesive to the under-surface of the article while it is in a horizontal position, applying a coating of glazing material on the adhesive coated surface by pressing the adhesive coated surface downwardly onto a surface bearing the glazing material, then passing the articles face down through a press for pressing the

glazing material into the adhesive coating and finishing the article preparatory to burning the same.

2. In a process for glazing a ceramic article, the steps of applying an adhesive to the undersurface of the article while it is in a relatively horizontal position by passing the article into pressure contact with a moving adhesive applicator, then applying to the adhesive covered undersurface of the article a coating of powdered glazing material by placing the undersurface of the article forcibly upon a moving element having an evenly distributed quantity of the glazing thereon, and then embedding the glazing material in the adhesive coated undersurface and finishing the article for firing by passing the article through a compressing means which acts upon both its upper surface and its undersurface.

3. In a process for glazing a ceramic article, the steps of applying an adhesive to the undersurface of the article while it is in a relatively horizontal position by passing the article into pressure contact with a moving adhesive applicator, then applying to the adhesive covered undersurface of the article a coating of powdered glazing material by placing the undersurface of the article forcibly upon a moving element having an evenly distributed quantity of the glazing thereon, and then embedding the glazing material in the adhesive coated undersurface and finishing the article for firing by passing the article through a compressing means which acts upon both its upper surface and its undersurface, the embedding of the glazing material in the adhesive covered undersurface and the finishing of the article for firing being carried on simultaneously.

In testimony whereof I affix my signature.

GEORGE F. WILDE.
